G. CROSSLAND.

PILE WIRE.

APPLICATION FILED JULY 28, 1915.

1,180,015.

Patented Apr. 18, 1916.

UNITED STATES PATENT OFFICE.

GEORGE CROSSLAND, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

PILE-WIRE.

1,180,015.

Specification of Letters Patent. Patented Apr. 18, 1916.

Application filed July 28, 1915. Serial No. 42,434.

To all whom it may concern:

Be it known that I, GEORGE CROSSLAND, a citizen of the United States, residing at Worcester, in the county of Worcester and State of Massachusetts, have invented a new and useful Pile-Wire, of which the following is a specification.

This invention relates to a pile wire of special construction and to devices for detachably securing a pile cutting knife thereto.

It is the general object of my invention to improve the construction of such wires, with increased economy of manufacture and efficiency in operation.

With this general object in view one feature of my invention relates to a novel construction of the wire itself by which the essential vertical rigidity of the wire is combined with increased lateral flexibility.

A second feature of my invention relates to the provision of improved means for detachably securing a pile cutting knife within a recess formed in the pile wire.

25 Further features of my invention relate to certain arrangements and combinations of parts which will be hereinafter described and more particularly pointed out in the appended claims.

30 Two forms of my invention are shown in the drawings in which—

Figure 1 is a vertical sectional view of certain portions of a loom with my improved pile wire supported thereby; Fig. 2 is an enlarged side elevation of the pile wire; Fig. 3 is an enlarged end elevation of the pile wire looking in the direction of the arrow 3 in Fig. 1; Fig. 4 is a partial longitudinal sectional view taken along the line 4—4 in Fig. 3; Fig. 5 is a view similar to Fig. 4 but showing a slight modification, and Fig. 6 is a top plan view of the device shown in Fig. 5.

Referring to the drawings, I have shown 45 my improved pile wire 10 as detachably secured at its rear end to a supporting blade 11 which in turn is secured to an upright bar 12, the blades 11 and bar 12 being suitably supported at the rear of the reed 13. 50 For a full description of the detachable connection between the wire 10 and the

blade 11, reference is made to the patent to Wattie, #790,016, dated May 16, 1905.

The pile wire 10 extends forwardly over a cloth supporting girt 14 and detachably 55 engages the rearwardly projecting edge of a cross plate 15, the girt 14 and the plate 15 being each suitably secured to the loom sides (not shown). The plate 15 is spaced above the cloth supporting girt 14, the fabric passing over the girt 14 and under the plate 15 to a take-up roll 16 of any usual form. At its rear edge the plate 15 is provided with a projecting flange 17 which engages a notch 18 formed in the front end or 60 head of the pile wire 10.

The wire 10 is of special construction and consists of two thin flat metal strips 10^a and 10^b (Fig. 6) extending longitudinally throughout the length of the wire, and secured to each other throughout substantially all of the inclined portion of the wire by soldering or in some other convenient manner. In the left hand portion of the wire, as viewed in the drawings, the strips 10^a and 10^b are slightly separated by interposed spacing strips 20 and 21 (Fig. 4). The strips 20 and 21 are longitudinally spaced to provide an opening 22 for a purpose to be described. At the right hand end of the 70 spacing strip 21 the side strips 10^a and 10^b are left free and unattached to each other for a short distance, as indicated at 23 between the dotted lines 23^a in Fig. 2. By thus leaving the strips unattached to each other for a short distance, the lateral flexibility of the pile wire is much increased, while the vertical rigidity remains unimpaired. 80

At the extreme left hand end the pile wire 90 10 is provided with a thickened end portion or head 24, in order to more firmly engage the plate 15. As shown in the drawings, this end portion comprises a single piece of metal having the notch 18 formed in its 95 front edge and also having a longitudinal groove 25 (Fig. 3) formed in its lower edge to receive the forward ends of the side strips 10^a and 10^b and the spacing strip 20.

The spacing strip 20, in the form shown 100 in Fig. 4, is provided with a recess 26 in its upper edge, said recess extending forwardly

to form a socket 27 under the head 24. The right hand end of the spacing strip 20 is also cut away to provide an undercut recess 28.

5 The detachable pile cutting knife 29 is formed of thin sheet steel and is designed to be inserted between the side strips 10^a and 10^b in the recess formed by the insertion of the spacing strip 20. At its right hand or rear end the knife 29 is provided with an inclined cutting edge 30 and the knife is also provided with an upward extension 31 by which it may be more readily handled. At its left hand end, the knife 15 has a lug 32 adapted to engage the socket 27 and at its right hand end it has a depending portion 33 adapted to project downwardly through the opening 22 and forwardly into the recess 28.

20 The knife may be readily inserted from above within the recess in the pile wire, the portion 33 passing downward through the opening 22 previously described. The knife is then moved to the left or forwardly to 25 bring the lug 32 and the portion 33 into the socket 27 and recess 28 respectively. It will be evident that the knife cannot therefore be removed except by a rearward and upward movement relative to the pile wire 10.

30 In the modified form shown in Figs. 5 and 6, the socket 27 and the lug 32 are omitted and a cross pin 35 is positioned to engage the upper edge of the knife 290. The construction of the knife is otherwise as shown 35 in Fig. 4 and the operation and effect of the construction is identical.

The operation of the device will be readily apparent from the drawing, the warp threads A passing through the reed 13 in 40 the usual manner and forming the pile loops over the wires 10. These loops are gradually forced forwardly by the beating up of the reed and as they move forwardly they engage the cutting edge 30 of the knife 29, 45 the loops being thereby severed to form the pile of the fabric.

Should certain of the knives become dull or have their cutting edges injured in any way these knives may be easily removed and 50 others substituted therefor. Furthermore the knives themselves being formed of thin sheet material are relatively inexpensive and the entire construction can be much more economically manufactured than is the case 55 when the knife is formed as an integral part of the pile wire.

Having described two forms of my invention it will be evident that other changes and modifications can be made therein by 60 those skilled in the art without departing from the spirit and scope thereof as set forth in the claims and I do not wish to be otherwise limited to the details herein disclosed, but

What I do claim is:—

1. In a loom, in combination, a reed, a cloth supporting girt, a cross plate spaced above said girt, a pile wire supporting blade positioned at the rear of the reed, a pile wire extending from said supporting blade across 70 said girt and engaging said cross plate, said pile wire having a recess in its upper edge, and a detachable pile knife fitting within said recess, and means to secure said knife against removal therefrom except by a combined rearward and upward movement. 75

2. In a loom, a pile wire, having provision at each end for detachably engaging suitable supports and formed of two thin flat metal strips firmly secured to each other throughout a portion of their length and secured to each side of thin spacing strips along another portion of their length, an intermediate portion of said metal strips being unattached to each other whereby increased flexibility of the pile wire is obtained. 80

3. In a loom, in combination, a pile wire, and a detachable knife, said pile wire having provision at each end for detachably engaging suitable supports and being formed of two thin flat metal strips firmly secured to each other throughout a portion of their length and secured to each side of thin spacing strips along another portion of their length, said knife and said spacing 90 strips having engaging portions by means of which said knife is retained in position on said pile wire and is removable therefrom in a rearward and upward direction only. 95

4. In a loom, in combination, a pile wire 100 and a detachable knife, said pile wire being formed of two thin flat metal strips extending throughout the length of the wire and firmly secured to each other throughout a major portion thereof, said strips being secured to each side of thin spacing strips along another portion of their length and having provision for detachably engaging the pile knife at two separated points, and said knife being positioned between said 105 metal strips and being removable therefrom in a rearward and upward direction only.

5. In a loom, in combination, a pile wire and a detachable knife, said pile wire being formed of two thin flat metal strips extending throughout the length of said wire, a thickened head portion secured to the front end of said strips, and means to form a recess between said strips adjacent said head portion, and said knife being formed of thin sheet steel and being detachably secured in 115 said recess. 120

6. In a loom, in combination, a pile wire and a detachable knife, said pile wire being formed of two thin flat strips of sheet metal, 125 separated at their forward ends by a thin sheet metal spacing strip, and a thickened head having a groove in its lower edge with-

in which the forward ends of said side strips and of said spacing strip are secured, and said knife being detachably secured in the recess formed between said side strips and above said spacing strip.

7. In a loom, in combination, a pile wire and a detachable knife, said pile wire being formed of two thin flat strips of sheet metal, separated at their forward ends by a thin

sheet metal spacing strip, and said knife being formed of thin sheet steel substantially equal in thickness to said spacing strip, and being detachably secured within the recess formed by said spacing strip between said side strips.

In testimony whereof I have hereunto set my hand.

GEORGE CROSSLAND.
